UNITED STATES PATENT OFFICE.

ANDREW G. GREIG, OF NEW YORK, N. Y., ASSIGNOR TO THE BIGELOW
CARPET COMPANY, OF MASSACHUSETTS.

DESIGN FOR CARPETING.

SPECIFICATION forming part of Design No. 30,451, dated March 28, 1899.

Application filed December 29, 1898. Serial No. 700,663. Term of patent 3½ years.

To all whom it may concern:

Be it known that I, ANDREW G. GREIG, a citizen of the United States, and a resident of the city, county, and State of New York, 5 have invented a new and original Design for Carpeting, of which the following is a specification.

My design, as shown in the drawing, consists in a new design for carpeting.
10 The design is characterized by large shield-like figures bounded by ornamental scroll and leaf-like outlines and bearing upon their face a central bouquet of flowers. In association with said shield-like figures festoons of flowers and foliage are arranged, sometimes depending from the shield-like figures and

sometimes connecting adjacent shield-like figures. The whole is arranged upon a suitable background.

The design is suggestive of the rococo period of ornamentation. 20

What I claim as new, and desire to secure by Letters Patent, is—

The design for carpeting substantially as shown and described. 25

In testimony whereof I have signed my name to this specification in the presence of two subscribing witnesses.

ANDREW G. GREIG.
